UNITED STATES PATENT OFFICE.

GEORGE R. WADSWORTH, OF CLEVELAND, OHIO, ASSIGNOR TO THE PEERLESS MOTOR CAR COMPANY, OF CLEVELAND, OHIO, A CORPORATION OF OHIO.

PRIMING DEVICE FOR INTERNAL-COMBUSTION ENGINES.

1,069,502.

Specification of Letters Patent.

Patented Aug. 5, 1913.

Application filed November 8, 1911. Serial No. 659,099.

To all whom it may concern:

Be it known that I, GEORGE R. WADSWORTH, a citizen of the United States, residing at Cleveland, in the county of Cuyahoga and State of Ohio, have invented a certain new and useful Improvement in Priming Devices for Internal-Combustion Engines, of which the following is a full, clear, and exact description.

10 This invention relates to internal combustion engines and particularly to certain improvements which concern the priming of the cylinders for starting purposes.

One of the objects of my invention is to 15 conduct the priming mixture to the cylinders from a source of supply without the necessity for a complicated system of piping which would add materially to the number of external parts.

20 Further, the invention aims to provide a means for conducting or conveying the priming mixture to the cylinders in a very effective manner by way of the main intake manifold but without having the priming mixture diluted by mixing with the contents of the manifold which may not be sufficiently rich in gasoline to ignite.

A further object is to provide a carbureter 25 having an auxiliary vaporizer which is employed for starting purposes and has associated with it means for causing the mixture to be of constant richness in gasoline, regardless of the rate at which the engine is cranked.

30 The above and other objects are accomplished by my invention, which may be briefly summarized as consisting in certain novel details of construction and combinations and arrangements of parts, which will 35 be described in the specification and set forth in the appended claims.

In the drawings, Figure 1 is a side view 40 of a portion of an internal combustion engine equipped with my invention, parts being broken away and omitted, and other parts being shown in section; Fig. 2 is a partial transverse sectional view substantially along the line 2—2 of Fig. 1, looking in the direction indicated by the arrows; Fig. 3 is a sectional view through the auxiliary vaporizer, substantially along the line 45 3—3 of Fig. 1, looking in the direction indicated by the arrows.

The internal combustion engine 10 may 50 be of any suitable construction and may

have any number of cylinders, a portion of a six-cylinder engine being here shown, the cylinders being cast in pairs. The engine is provided with a carbureter 11, which is connected to the cylinders of the engine by 60 a main intake manifold 12, which may be of any suitable form or construction. The carbureter includes a throttle valve 13, a main mixing chamber 14, and a main gasoline jet tube 15, which is connected in the 65 usual manner with the float controlled gasoline chamber 16. In addition to the above parts, I provide means for priming the cylinders of the engine, or supplying thereto independently of the main parts of the carbureter, a mixture for starting purposes. While it is immaterial, as far as certain features of my invention are concerned, as to the particular character of the source of the priming mixture, I here show the 70 source of the priming mixture in the form of an auxiliary vaporizer designated as a whole by the reference character 17. This auxiliary vaporizer includes a chamber 18 which constitutes in effect an auxiliary mixing chamber and incloses an auxiliary jet tube 19 which is connected to the float controlled gasoline chamber 16. The chamber 18 has near its lower end, air inlet openings 18a, so arranged that the air drawn therethrough will pass in part at least about the orifice of the jet tube so as to cause vaporization of the gasoline.

I am aware of the fact that it has been proposed heretofore to provide in a carbureter an auxiliary vaporizer which may or may not be used for the production of a mixture for starting purposes. Regardless of the particular function of the auxiliary vaporizer, it has been customary, so far as 90 I am aware, to conduct the mixture from the auxiliary vaporizer by a passageway which may be in the form of a cored opening or a separate pipe to the upper part of the carbureter, or to the lower part of the intake manifold directly above the throttle valve. In any event, the mixture produced by the auxiliary vaporizer enters the intake manifold and is drawn up into the cylinders 100 therethrough. This is not satisfactory for starting purposes, for the reason that this mixture at first may be of suitable richness in gasoline for ignition but before it enters the cylinders, it is more or less diluted by the contents of the main manifold. It is de- 105 110

sirable therefore, that this mixture be conveyed in its properly enriched state not to some part of the carbureter to the lower part of the manifold, but directly to the cylinders. To accomplish this object, I convey the mixture from the auxiliary vaporizer by means of a passageway in the form of a pipe 20, to the lower part of the manifold 12 or to the point where it has been proposed here-
 5 tofore to discharge the mixture. I also provide for conveying the mixture from this point to the cylinders, a small auxiliary intake manifold 21, which is located within the main manifold, as shown in the drawings.
 10 This inner auxiliary manifold is co-extensive with and follows the branches of the main manifold, as indicated in Figs. 1 and 2, and the branches of the auxiliary manifold discharge the mixture into the cylinder castings, or at the points where the mixture is normally discharged from the branches of the main manifold. In this manner, the mixture for starting purposes is conveyed directly to the cylinder by way
 15 of the main manifold, but without having the mixture diluted by the contents of the main manifold, and without a complicated system of exterior piping, which is obviously objectionable. It will be apparent also that this same arrangement of one intake manifold within the other might be employed as well with a different form of source for the priming mixture, such for example, as a priming pump, the discharge
 20 side of which might very well be extended to the lower end of the intake manifold, and connected to the lower end of the inner intake, the same as I here connect the pipe 20.

When it is desired to start the engine by cranking or otherwise turning the engine over, the throttle valve 13 will preferably be closed so that the suction created by the movement of the pistons is all directed through the inner manifold 21, pipe 20, and auxiliary vaporizer. After the engine is up to speed, there will be little suction through the auxiliary intake manifold and pipe 20, the throttle valve then of course being opened and the vaporization for normal engine operation taking place in the main portion of the carbureter, which then functions in the usual manner. In fact, I prefer to provide in the pipe 20 between the manifold and auxiliary vaporizer, a valve 22, by
 45 which the auxiliary vaporizer may be put out of service entirely after the engine is started. This valve will be operated from any suitable point.

Another feature of my invention resides in an improvement which I have effected in the auxiliary vaporizer, to cause a mixture of constant or uniform richness in gasoline, regardless of the rate at which the engine is cranked. This is of no little im-
 50 portance when it is considered that the mix-

ture which is supplied to the engine for priming purposes, should have a certain degree of richness, although under ordinary conditions and with an ordinary vaporizer the richness varies with the rate at which the engine is cranked. To obtain a uniform mixture, regardless of the rate at which the engine is cranked, I provide in the chamber 18 about the jet tube 19 a so-called floating sleeve 23 having a substantially cylindrical lower portion, which surrounds and slides on the jet tube 19, and a flaring upper portion, the top of which has a fairly close working fit within the inner cylindrical wall of the chamber 18. The jet tube is substantially square in cross section, as indicated in the cross sectional view of Fig. 3, the sleeve bearing on the corners which are slightly rounded. This construction provides between the sleeve and tube passageways 24. The sleeve is provided near its lower end with openings 25 through which air may pass into the passageways between the tube and sleeve, or directly into the chamber above these passageways.

When the engine is being cranked, the suction causes the sleeve to rise a certain amount, depending upon the rate at which the engine is cranked. The greater the suction, the more the sleeve rises. However, the position of the sleeve determines partially the velocity and direction of the air which passes upwardly about the gasoline orifice. When the sleeve is in substantially its lowermost position, practically all of the air passes through the rather restricted passageways 24, between the sleeve and the jet tube. The higher the position of the sleeve, the less the percentage of air which passes through the restricted passageways 24, and the greater the percentage which passes directly through the larger openings 18^a and 25 over the orifice. Hence, this sleeve tends to regulate the velocity of the air which passes about the orifice by controlling the course of the air and the effective size of the air opening or openings which surround the orifice. In this manner, the velocity of air about the orifice is substantially constant, and the richness of the mixture is substantially uniform regardless of the rate at which the engine is cranked.

Having described my invention, I claim:

1. In combination in an internal combustion engine having one or more cylinders, a main source of explosive mixture, a main manifold connecting the same to the cylinder or cylinders, an auxiliary source of mixture, and a second intake manifold within the main manifold and connecting said auxiliary source to the cylinder or cylinders.
2. In combination in an internal combustion engine having a plurality of cylinders, a main source of explosive mixture, a main manifold connecting the same to the cylinder or cylinders.

ders, a valve between the main source and the cylinders, an auxiliary source of fuel, a pipe connecting the same to the manifold above the valve, an auxiliary intake manifold located within the main manifold and connected to said pipe.

3. In combination in an internal combustion engine having one or more cylinders, a carbureter provided with a main gasoline jet tube and a main mixing chamber, and with an auxiliary jet tube and auxiliary mixing chamber, a main intake manifold connecting the main mixing chamber with the cylinders, and a second intake manifold located within the main intake manifold and connecting the auxiliary mixing chamber with the cylinders.

4. In combination in an internal combustion engine, one or more cylinders, a car-

bureter having a throttle valve, a main jet tube and a main mixing chamber, an auxiliary jet tube, and an auxiliary mixing chamber, a main intake manifold connecting the main mixing chamber with the cylinders, a passageway extending from the auxiliary mixing chamber to the intake manifold just above the throttle valve, and an auxiliary intake manifold located within the main manifold for conveying mixture from the upper end of said passageway to the cylinders independently of the contents of the main manifold.

In testimony whereof, I hereunto affix my signature in the presence of two witnesses.

GEORGE R. WADSWORTH.
